UNITED STATES PATENT OFFICE.

WILLIAM H. FISHER, OF ALTOONA, PENNSYLVANIA, ASSIGNOR OF ONE-THIRD TO
ROBERT D. ELDER, OF JUNIATA, PENNSYLVANIA.

ADJUSTABLE WRENCH.

Application filed February 5, 1925. Serial No. 7,040.

To all whom it may concern:

Be it known that I, WILLIAM H. FISHER, a citizen of the United States of America, residing at Altoona, in the county of Blair and State of Pennsylvania, have invented new and useful Improvements in Adjustable Wrenches, of which the following is a specification.

The purpose of the invention is to provide a wrench of a simplified construction and equipped with adjusting means enabling it to be instantaneously adjusted to the size of a nut or bolt head to be operated upon; to construct the adjustment in the form of a lock which will preclude the spreading of the jaws due to the pressure imposed upon them in the nut or bolt turning operation; and to construct the lock in such a way that the movement of the jaws toward each other may be readily effected by relative sliding movement imparted to the parts, so that where the initial adjustment, as it should be, leaves a greater spread or separation between the jaws than is necessary for the work in hand, the jaws may be moved, after the application of the wrench to the work, to bring them into snug engagement therewith.

With this purpose in view, the invention consists in a construction and combination of parts of which a preferred embodiment is illustrated in the accompanying drawings, wherein:

Figure 1 is a side elevational view, of a wrench constructed in accordance with the invention;

Fig. 2 is a similar view of one of the members of which a duality comprise the tool;

Fig. 3 is a similar view of the other member;

Fig. 4 is a detail elevational view of a portion of one of the members showing the lock mounted therein;

Fig. 5 is a transverse sectional view on the plane indicated by the line 5—5 of Fig. 1; and

Fig. 6 is a transverse sectional view on the plane indicated by the line 6—6 of Fig. 1.

The wrench comprises a duality of members A and B, each of which comprises a handle section and a jaw section. The handle section 10 of the member A has integrally formed therewith the jaw sections 11 and 12 at opposite ends, these jaw sections being in the form of hooked extensions of

the handle section. At an intermediate portion in its length, it is channeled, as shown at 14, and at opposite side walls of the channel is serrated as shown at 15 to provide angularly inclined teeth for engagement with complementary teeth on the nose extension 16 of a locking pawl 17, the locking pawl being of a thickness corresponding to the depth of the channel 14 so as to be enclosed by the latter and the handle section 18 of the member B when the two members are attached. Jaw sections 19 and 20 complementary to the jaw sections 11 and 12 are formed at the extremities of the member B, the member A at the extremities of the handle section being formed with the guide channels 21 and 22 for the extremities of the handle section 18, so that relative longitudinal movement of the handle sections may be effected to adjust the complementary jaw sections toward and away from each other.

The attaching means by which the members A and B are secured together consist of screw studs 23 which pass through oval holes 24 in the handle section 18 of the member B, the major diameters of the ovals being in the direction of the length of the handle member. These screw studs threadingly engage holes 25 in the member A. The oval holes 24 thus provide for movement of the member B longitudinally of the member A, movement in one direction obviously tending to shift the jaw member 20 toward the jaw member 12 and in the opposite direction to reduce the spacing between the jaw members 11 and 19.

The serrations 15 being carried by the member A, it is necessary, in order that a lock may be effected, that the locking pawl be carried by the member B, and to this end the latter is provided with an eye 26 and tangential to this eye, the handle section 18 is slotted for the reception of a flat spring 27 which invades the eye to bear upon a flat 28 of the pivot stud 29, the stud being mounted in the eye 26 and extending through an oval hole 30 in the handle section 10 to receive a nut 31 abutting said handle section on the outer face. The stud 29 carries the locking pawl 17 which is keyed to it, as at 32, and the nut 31, being in the form of a wing nut, enables the stud 29 to be turned and thus the locking pawl shifted out of engagement with the serrations 15. The turning of the stud 29 to disengage the pawl 17 from the

serrations 15 results in flexing of the spring 27 because of the flat of the stud 29 which it engages and thus when pressure is released from the nut 31, the spring serves to return the pawl to locking position, which is the position which it should have when the desired adjustment of the jaw members is obtained.

The stud 29 has a shoulder 29^a against which the nut or handle 31 engages. The stud 29 is also reduced beyond this shoulder and threaded and on which the nut or handle 31 is secured. The reduced portion of the stud is threaded and to fasten the nut or handle on the reduced portion, the extremity of the reduced portion may be peened over or swaged, as at 31^a, or the longitudinal side walls of the nut or handle 31 can be partially indented so as to rupture the threads of the reduced portion to prevent the nut turning relatively to the stud. In other words, by this means the nut, when manually manipulated, will rock the stud for the purpose of moving the locking pawl 17.

25 The invention having been described, what is claimed as new and useful is:

1. A wrench comprising handle members of which each carries one of a pair of complementary jaw elements, one of said handle members on one face thereof being channeled out to provide a pocket, the bottom of which is slotted, said face of such handle member at its opposite ends having guide channels for the slidable reception of the other handle member which has guide slots at its opposite ends, means passing through the second slots

and connected to the first handle member to unite both members, the side walls of the pocket having teeth, and a pawl mounted in the pocket engaged with the teeth and operatively carried by the second slotted handle member, with means passing through the slot in the bottom of the pocket including a device for disengaging the pawl from the teeth to adjust one handle member to the other.

2. A wrench comprising a handle member with one side face provided with an elongated depressed pocket and guide channels adjacent the ends of the member, the pocket and the channels being on the same side face of the member, a second handle member mounted in the guide channels, whereby both handle members may slide in parallelism relative to each other, means for retaining one handle member connected to the other, the opposite ends of both handle members having complementary jaw elements, the jaw elements being movable toward and from each other in alignment with the handle members, the bottom of the pocket having an elongated slot, and means carried by one handle member and operatively mounted in the pocket for retaining the handle members in relatively different adjusted positions, said means having a device passing through and operative longitudinally in the slot in the bottom of the pocket for actuating the retaining means to permit the members to be adjusted.

In testimony whereof I affix my signature.

WILLIAM H. FISHER.
